Inventor.

United States Patent Office.

WILLIAM PARKIN, OF TAUNTON, MASSACHUSETTS, ASSIGNOR TO REED & BARTON, OF SAME PLACE.

Design No. 4,438, dated October 25, 1870.

DESIGN FOR CASTER-BOTTLES.

The Schedule referred to in these Letters Patent and making part of the same.

To all whom it may concern:

Be it known that I, WILLIAM PARKIN, of Taunton, in the county of Bristol and State of Massachusetts, have invented and produced a new and original Design for Bottles for Casters; and I do hereby declare the following to be a full, clear, and exact description of the same, reference being had to the accompanying drawings making a part of this specification, in which—

Figure 1 is a side view of a vinegar-cruet, and Figure 2, a similar view of a mustard-pot.

Both fashioned after my design, and adapted for use in connection with table-casters.

The object of this invention is to provide for the public an improved design for caster-bottles, said design consisting in the peculiar shape and ornamentation of the bottles, as shown and hereinafter described.

The bottle is of glass, made in such shape that any horizontal section below the lip-flange or ferrule will be a perfect square, the lip-flange or ferrule *a a* being annular.

The bottle swells out slightly from the bottom to the shoulders *c c*, whence it diminishes in a graceful curve to the neck.

Its corners are serrated, and its flat sides ornamented with a flower or leaf, *e*, ground upon the glass.

The stopple of the cruets consist of a square or oblong block, *m*, surmounted by a pyramidal top with

edges beveled, the edges of the block being serrated like those of the bottle.

This block is attached to the ground-glass plug that fits into the neck of the bottle, by means of a contracted or scalloped neck, *n*, having its edges beveled.

The mustard-pots, of course, must be provided with a cover instead of a stopple. This cover consists of a cone, *I*, resting on a flange, *i*, that fits upon the upper edge of the ferrule *a*, being hinged thereto on one side.

The cone is contracted or nearly truncated at its upper end, as seen at *a*, and is surmounted by a diminutive cylindrical column, *r*, having a wide flat flange or collar, *s*, around it, every part of the cover and ferrule being plain, smooth, and polished bright.

Having thus described my invention,

What I claim as new, and desire to secure by Letters Patent, is—

1. The design for caster-bottles, consisting in forming them square, as shown and described.
2. The design for the side ornament *e*, as shown and described.
3. The design for the cover of the mustard-pot, as shown and described.

WILLIAM PARKIN.
